UNITED STATES PATENT OFFICE

ANDREW A. BEEMAN, OF BOYNE CITY, MICHIGAN

HOE

Application filed October 3, 1932. Serial No. 635,953.

This invention relates to a hoe and more particularly to a hoe which is adapted for weeding purposes.

Briefly described, my hoe consists of a flexible and narrow blade, such blade having a toothed edge construction, and being resiliently supported whereby the shocks of impact due to the blade hitting stones or obstacles of any kind are damped out before reaching the handle member of the hoe, such obviously being advantageous.

Also, it is desired to point out that the thickness of the blade together with its flexible mounting, permits a certain vibration to be set up in the blade and this slight vibration or movement causes the passage of the blade through loose dirt to be facilitated.

Another object of my improved hoe lies in the mounting of the blade at a very slight angle to the surface of the ground. This permits the hoe to be used in long sweeping strokes approximately two and one-half feet in length and hence it is apparent that a much greater area of ground can be covered with this type of hoe than with any other hoe now in existence.

Another feature which is tied up with the angle at which the blade is mounted is the supporting means for the blade, such supporting means being fastened to the blade near either end thereof and then extending inwardly at a considerable distance from the blade whereby an open area is had centrally of the blade whereby the weeds, which have been cut or uprooted, may pass over the blade and under the blade mounting, thus getting them out of the way in a direct and efficient manner. Such is in contradistinction to the usual type of hoe which permits the destroyed weeds to fall in with those which are to be cut. In fact, the projected area of the blade upon a vertical plane is only about one-fifth of the projected open area between the top of the blade and the cross bars supporting the blade. Hence, it will be obvious that the small weeds can readily pass between the blade and the horizontal portions of its supporting members whereas the larger weeds pass above the said supporting members.

Another advantage of my device resides

in the mounting of the same upon the wooden handle, thus providing a fitting which securely holds the several parts in position.

Yet another extremely important advantage lies in the preferred toothed edge construction of the blade whereby the weeds are gripped and held but usually not cut entirely off and thus the weeds are bodily pulled up by their roots and then the roots are stripped of dirt and mutilated and skinned in parts by further movement of the blade and thus there is no chance that the weeds will again take root and grow. The blade during the above operations, passes through the loam a slight distance below its surface.

Further advantages will be apparent as the description proceeds.

In the drawings:

Fig. 1 is a perspective view of the preferred form of my invention.

Fig. 2 is a cross sectional view taken along the line 2—2 of Fig. 1.

Fig. 3 is a cross sectional view through the lower end of the handle.

Fig. 4 is a view taken along the line 4—4 of Fig. 3.

Fig. 5 is an enlarged view showing the toothed edge construction of the blade.

Fig. 6 is a sectional view illustrating the mounting of the blade.

Fig. 7 is a perspective view of a modification of my device, this being particularly useful in hoeing a row of small plants.

Fig. 8 is a cross sectional view through the lower end of the handle member of Fig. 7.

Similar numerals refer to similar parts throughout the several views.

In the drawings, numeral 10 indicates a handle member, which is tapered at its lower end, see Fig. 3, and which has recesses 11 formed therein. See Fig. 4. A metal ferrule 12 is adapted to be wedged upwardly over the tapered portion of the handle member after rod members carrying the hoe blade, have been inserted therein, and the ferrule is held in place by the pin 13.

Rod members have upper ends 14 which are continued in short parallel portions 15 and then bent outwardly to form oppositely extending arms 17, then continued in substan-

tially semi-circular bends 18 and which finally terminate in beveled portions 19. See Fig. 2.

A flexible blade 20 is notched as indicated 5 at 22, these notches having a pitch of approximately one-half inch. The blade 30 is extremely flexible and resilient and is connected onto the portions 19 by means of the rivets 21.

10 *The operation*

The operation of the preferred form described is easily understood. The user grasps the handle of the hoe and with long sweeping strokes urges the blade parallel to but slightly under the surface of the ground, the blade cutting and gripping and tearing the weeds from the ground and finally stripping their roots of excess dirt whereby killing 20 thereof is assured. In this regard, it is to be noted that the toothed construction materially aids in gripping the tougher weeds and thus enabling the user to pull them up by their roots. Also, should a rock or stone 25 be encountered, the resiliency of the blade prevents the full force of the impact from being transferred to the handle member.

Also, as previously mentioned, the resistance to the passage of the hoe through the 30 weeds is materially lessened due to the small horizontal area of the thin metal blade and also to the large opening immediately above the central portion of the blade.

Also, the rod supporting means of my hoe 35 curves upwardly above the axis of the handle, see Fig. 2, and consequently aids in the production of a balanced construction although the center of gravity always urges the hoe to a working position.

40 Referring now to the modified form of construction, 40 indicates the handle member tapered and recessed as at 41, said recesses receiving straight portions 42, these portions abutting as at 43, see Fig. 8, and then continuing outwardly and downwardly as at 44, 45 see Fig. 7, and terminating in bifurcated portions 45. Blades 46, toothed as at 47, are riveted at 48 onto the bifurcated arms 45 and those blades are spaced apart as clearly 50 shown in Fig. 7.

The straight portions 42 are welded, if desired, at their contact surfaces 43. A metal ferrule 50 wedges upwardly on the tapered portion of the handle and holds the members 55 42 in secure relationship to the handle, a pin 51 securing this connection.

60 In the above described modified construction, the handle is positioned sufficiently high to permit the passage of small plants thereunder. The blades 46 of the hoe being utilized on opposite sides of the row of plants. Thus, both sides of the row may be worked upon in a single operation.

65 In this double construction the same type of connection to the handle member is had,

the ferrule 50 being permitted to slide downwardly along the members 42 until they are inserted in their respective recesses and then being wedged upwardly and held in position by means of the pin 51. This type of ferrule connection is thought to be new and it produces a long lived and sturdy connection as will be appreciated.

Should one of the blades 46 encounter a 75 rock no damage to the plants will be done as the opposite blade 46 will be in contact with the earth and hence sidewise movement of the hoe is prevented. Similarly, in the preferred construction the blade is of sufficient length to accomplish this same result.

80 In closing, I desire to point out that my structure is much better than any hoe or similar device now on the market and such is attested by the reception it receives wherever shown. It is a three purpose hoe, first, a weeding hoe, second, a hoe which will work the weeds out of the ground and clear 85 their roots, and third, it is a hoe which will kill plants.

90 Without limiting myself to the particular embodiments of my invention illustrated and explained above, and desiring to protect my invention in the broadest manner legally possible, what I claim is:

95 A weeding hoe consisting of a handle member, rod members extending in parallelism and alongside of said handle member for a short distance and then extending outwardly in opposite directions at right angles to the axis of the handle and then being bent at right angles in planes parallel to each other substantially in the form of a half-circle and terminating in a bevelled portion interiorly of said half-circle, a flexible steel blade fastened to said bevelled portions thereby 100 locating said blade at an angle of substantially 45° to the axis of the handle member, said rods being of light construction, and means slidable along the said parallel portions of the rod members for engagement 105 with the said end portion of the handle member.

110 In testimony whereof I affix my signature.
ANDREW A. BEEMAN.
